UNITED STATES PATENT OFFICE.

ALBERT H. REEKS, OF TORONTO, ONTARIO, CANADA.

AUTOMOBILE LAMP.

Application filed May 23, 1921. Serial No. 471,964.

To all whom it may concern:

Be it known that I, ALBERT H. REEKS, a subject of the King of Great Britain, and resident of the city of Toronto, county 5 of York, Province of Ontario, in the Dominion of Canada, have invented certain new and useful Improvements in Automobile Lamps, described in the following specification and illustrated in the accompanying 10 drawings, that form part of the same.

The principal objects of the invention are, to devise a light for motor cars which will throw a light forwardly and downwardly to thoroughly illuminate the road giving ample side light without throwing direct and glaring rays upwardly, thus avoiding the blinding of the drivers of approaching vehicles.

The principal feature of the invention consists in the novel arrangement of the lamp in relation to the reflector and in the construction of the reflector with a centrally located hole into which the bulb of the lamp is inserted and the lamp socket is arranged 20 in front of the reflector being supported by an opaque semi-circular plate extending across the upper half of the reflector, whereby rays of light from the upper half of the reflector are intercepted and concentrated 25 upon the lower half and are projected forwardly from the said lower half.

In the drawings, Figure 1 is a front view of my improved lamp.

Figure 2 is a vertical sectional view.

Numerous forms of light dimmers and reflectors have been devised from time to time in order to prevent "head light" glare which is so dangerous to traffic and I have found by extensive experiment that to obstruct the 35 upper half of the reflector and invert the position of the lamp so as to bring the light element thereof close in to the reflector produces the most remarkable results.

In order to get the lamp into the proper 45 position I find it necessary to pierce the reflector and as shown in the accompanying drawings, I construct my improved lamp with a deep converging inner rim 1 at the smaller diameter of which is secured a circular plate 2 having a semi-circular orifice 3 cut therein.

A parabolic reflector 4 extends inwardly

from the orifice in the plate 2 and the centre of this reflector is pierced with a hole 5. This hole is approximately one inch in diameter. 55

A lamp socket holder 6 is fixed to the plate 2 centrally thereof in horizontal alignment with the axis of the reflector and the lamp 7 is inserted in the socket arranged in the holder with its bulb projecting inward toward the reflector.

The glass of the bulb fits close in to the edge of the hole 5 in said reflector. The light emanating from the lamp is projected forwardly from the lower half of the orifice 65 3 in the plate 2 with a clear cut transverse upper limitation which may be set at any height by the tilting of the lamp. The rays are definitely restricted by this arrangement of the plate but the light projected from the 70 lower half of the reflector is such as to illuminate the road in front of the vehicle in a most remarkable manner. It throws a white unspotted light on the roadway in a wide angle and gives excellent driving light so 75 that the driver may clearly see on either side of him the condition of the road and it also projects the light well forward to give ample illumination of the road ahead and by actual test shows for a single lamp a spread 80 of thirty feet at a distance of 100 feet from the lamp with practically no rays rising above four feet.

When two lamps are used and focused together the light is of course greatly increased. 85 The rays projected seem to be diffused and free from glare and will meet the most rigid requirements of "non-glare" laws.

The device is very simple and is cheap to install in head lamps. The outer face of the 90 plate 2 and the inner rim 1 are preferably enameled white.

What I claim as my invention is:—

In an automobile headlight, the combination with the lamp casing, of a deep convergent rim extending inwardly from the glass, a rigid circular plate secured at the inner edge of said rim, said plate having a semi-circular opening in the lower half, a reflector arranged back of said plate, and a lamp supported from the upper portion of said plate and extending into close proximity to said reflector. 95 100

ALBERT H. REEKS.
